SLAB SEPARATING DEVICE

Mashel F. Pettler, Beaver Falls, Pa.

Application May 10, 1940, Serial No. 334,383

4 Claims. (Cl. 125—23)

This invention relates to improvements in apparatus for separating fired clay slabs and it is among the objects of the invention to provide a simple and economical device for separating relatively thin fired clay slabs with a minimum of breakage.

Recent developments in the building industry employ thin brick veneer slabs for mounting on the sidewall of dwellings, such slabs being produced by wire-cutting a full-size brick to produce seven slabs. After cutting, the brick is fired the same as a whole brick, and the slabs are separated after firing.

Considerable breakage results from separating the fired slabs by hand, which is eliminated by the present invention through the use of high speed reciprocating tools.

The invention will become more apparent from a consideration of the accompanying drawing constituting a part hereof in which like reference characters designate like parts and in which:

Fig. 1 is a top plan view of a slab separating machine embodying the principles of this invention; and

Fig. 2 an end elevational view thereof with a portion of the drive pulley cut away.

In the drawing, the numeral 1 designates a supporting table on which is journaled a shaft 2 carrying a belt pulley 3 driven by a motor 4 mounted on a transverse support 5 of the table. Shaft 2 is journaled at 6, 7 and 8 and a gear wheel 9 is mounted to rotate with the shaft. A plurality of slide bars 10 are mounted in journals 11, the bars 10 having a round end 12 for engagement with the teeth 13 of the wheel 9, as shown in Fig. 2.

The opposite ends of the slide bars 11 are provided with slotted heads 14 for receiving cutters 15 having a wedged tip 16 which constitute the cutting edges for separating the slabs 17 which are scored as shown by dotted lines in Fig. 1. Coil springs 18 abut against the slide bearing 11 at one end and the heads 14 of the slide bars at the other end to hold the bars free of the teeth 13 of wheel 9. Angle brackets 19 are mounted on the table to constitute abutments for the slide bar heads 14, the brackets being provided with slots 20 through which the cutter 15 projects.

To properly align the fired clay brick with the cutter point 16, an adjustable angle bracket 21 is mounted on the angle bracket 19 by means of a bolt 22 extending through a slot in the angle bracket 19. The bolt is provided with a wing-nut to facilitate adjustment to space the edge of the angle bracket 21 to conform to the thickness of the slabs to be separated. This is clearly shown in Fig. 1 of the drawing.

To separate the slabs, it is only necessary, after proper adjustment of the bracket 21 has been made, to hold the slab 17 against the edge of the bracket 21 and press it against the cutting bit 16 of the reciprocating tool. By pressing the fired clay block against the cutting point 16 and pushing the cutter bar 10 against the tension of the coil spring 18, the rounded end 12 of the bar engages the teeth of the wheel 9, which subjects the bar to a very rapid reciprocatory movement that quickly and safely separates the slabs without breakage. As the slabs are separated the successive wire-cut sections align themselves with the cutting bit to become separated.

While the invention may have other uses, it is primarily intended for the separation of fired clay articles as herein described.

I claim:

1. A machine for separating fired clay slabs comprising a cutting tool mounted on a flat supporting table, a toothed wheel having a relatively large number of angularly spaced teeth for engagement with one end of the cutting tool, spring means normally biasing the tool away from the teeth of the wheel, and a drive for the wheel to subject the cutting tool to rapid reciprocatory movement when pressed against the wheel.

2. A machine for separating fired clay slabs comprising a cutting tool mounted on a flat supporting table, having a cutting point, said cutting tool having a socket end for receiving the cutting element and being rounded at the opposite end thereof, a wheel having a plurality of teeth adapted for engagement with the rounded end of the cutter bar, a coil spring engaging the cutter bar to resiliently bias the rounded end of the bar away from the teeth of the ratchet wheel, and drive means for said wheel.

3. A machine for separating fired clay slabs comprising a toothed rotary wheel mounted with its axis substantially in the plane of a support, a reciprocating separating cutting tool mounted on said support in alignment with and adapted at one end to contact the teeth of the wheel, a stop plate at one end of the reciprocating member, a coil spring biasing the reciprocating member away from the wheel whereby, by application of the clay body to be separated against the cutting point of the tool, the reciprocating member is brought in engagement with the teeth of the wheel to subject the same to a rapid reciprocatory movement.

4. Apparatus as set forth in the next preceding claim having an adjustable angle bracket on the support for spacing the clay body relative to the cutting point.

MASHEL F. PETTLER.
